CHAIR WITH AUTOMATICALLY SHIFTABLE SEAT AND ADJUSTABLE BACK

Roy A. Cramer, Kansas City, Mo.

Application December 1, 1950, Serial No. 198,654

8 Claims. (Cl. 155—77)

1

This invention relates to chairs and more particularly to improvements in posture chairs of the general swivel type having a shiftable seat.

The principal object of the present invention is to provide a chair of this character having a seat shiftable forwardly and the front portion upwardly when the user shifts his body to the back of the chair.

Other objects of the invention are to provide a chair of this type wherein as the back is tilted rearwardly the seat automatically moves forwardly and the forward portion upwardly and the back portion tilts backwardly conforming to the back of the user at the extreme back tilting movement; to provide a mounting for the seat wherein the weight of the user will cause a substantially balanced action of the seat on the mounting mechanism wherein slight pressure backward on back of the chair will cause the seat to move forwardly and the front portion upwardly thus securing a natural pivotal action of the upper and lower portions of the user's body; to provide means mounted on the tilting mechanism frame for adjustably and tiltably mounting the back of the chair thereto; to provide a frame for the seat of the chair; to provide means for slidably mounting the seat frame on the tilting mechanism frame for moving the seat portion forwardly or backwardly relative to the back of the chair; to provide means for resiliently mounting the back of the chair with respect to the tilting mechanism; to provide spring tension means for varying shiftability of the chair seat; and to provide for mechanical adjustment of the tilting back mechanism.

Further objects of the present invention are to provide means for providing the correct balance of the chair and its occupant with respect to the chair base at various angles of tilt of the chair back; to provide means for mounting the tilting mechanism rotatably on the standard and base of the chair; to provide a cam roller mounting means for the seat operable in trackways so that when the user shifts his weight rearwardly the seat and back will tilt backwardly and shift forwardly to substantially the user's center of gravity to the vertical center of the swivel member support to produce a comfortable shifting movement and reduce the hazard of tipping the chair over backwards; to provide adjustable spring tension means for shifting movement of the trackways in the seat tilting mechanism with respect to the cam rollers; to provide shock absorbers at the limits of the cam track movements; to provide a bumper on the lower edge of the

2

seat to prevent marring of articles generally contacted by surrounding objects; and to provide a chair of this character simple, economical to manufacture and efficient in operation.

In accomplishing these and other objects of the present invention, I have provided improved details of structure, the preferred forms of which are illustrated in the accompanying drawings, wherein:

Fig. 1 is a side elevational view of my invention.

Fig. 2 is an enlarged side elevation of the seat and back portion with parts broken away to better illustrate the invention.

Fig. 3 is a bottom plan view of the seat.

Fig. 4 is a sectional view on the line 4—4, Fig. 3.

Fig. 5 is a perspective view of the spider for supporting the seat, showing the tension springs, one spring being shown in spaced relation thereto.

Fig. 6 is a transverse sectional view through the forward portion of the housing containing the tilting mechanism.

Fig. 7 is a sectional view taken on the line 7—7, Fig. 3 showing the position of the cam tracks relative to the roller wheels when the chair is in normal position.

Fig. 8 is a sectional view similar to Fig. 7 showing the position of the cam tracks when the seat is tilted.

Referring more in detail to the drawings:

1 designates a chair embodying the features of my invention comprising a base 2, a pedestal or standard 3 suitably mounted in the base for supporting a tilting mechanism 4 for supporting a seat 5 on which are mounted arms 6 and 7 and having a back 8.

The base 2 consists of a plurality of radiating arms 9 the outer ends being curved downwardly and mounted therein are casters 10. The base is cast in one piece and includes a depending housing 11 and an upstanding boss 12 at the top of the base, the housing being hollow and accommodating the standard 3 secured therein.

45 A spider 13 is provided for mounting of the tilting mechanism and also for supporting of the seat 5 as will later be described. The spider 13 comprises a body portion cast in one piece and has depending sides 14 and 15 flared outwardly forming a forward portion 16 and having a pair of arms 17 and 18 extending outwardly with the rear thereof terminating in a cross member 19. Formed approximately at the juncture of the arms 17 and 18 and the depending sides 14 and 55 15 of the body of the spider is a depending hous-

ing 20 providing a socket 21 for receiving the upper end 22 of the standard 3 to rotatably mount the tilting mechanism on the standard. Located near the upper end of the standard 3 is an annular groove 23. The rear of the housing 21 is provided with a transverse threaded opening 24 adapted to receive a set screw 25 having its inner end engaging in the annular groove 23 for retaining the spider on the standard.

The forward portion 16 of the spider has a downwardly extending flange 26 the ends of which are connected with outwardly flared sides 14 and 15 of the spider by blocks which form supports 27 and 28 for a shaft 29. The shaft 29 extends through the supports transversely of the spider and mounted on the ends of the shaft 29 are ball bearing cam rollers 30 and 31. The rear portion 19 of the spider is similarly provided with supports 32 and 33 for a shaft 34 which extends outwardly from the supports and mounted on the ends of shaft 34 are ball bearing cam rollers 35 and 36. The rear portion 19 of the spider is provided with upstanding flange portions 37 and 38 which are provided with cylindrical recesses 39. The recesses are provided with radial slots 40, as best illustrated in Fig. 5, for a purpose later described.

A housing 41 is provided for the tilting mechanism which is substantially rectangular in shape and has depending sides 42 and a forward end 43. The rear portions of the side are tapered as indicated at 44 (Fig. 8) and the extreme rear end is flanged downwardly at an angle, as indicated at 45. The housing is provided with a substantially flat top 46 having an embossed portion forming a raised plate member 47 (see Figure 4) for a purpose later described.

Secured to the inner portions of the respective sides 42 of the housing by welding or other suitable means are cam track plates 48 and 49 having inwardly turned upper and lower flanges 50 and 51 forming trackways 52 for the cam rollers 30 and 31 at the forward portion of the housing for the tilting mechanism. The cam plates are provided with enlarged portions 53 at their rear ends and the lower edges thereof are arcuately tapered as indicated at 54 (Figs. 7 and 8) which are also flanged as indicated at 55 and form bearing surfaces 56 for the cam rollers 35 and 36. The enlarged ends 53 of the cam tracks are provided with reinforcement plates 57 and are secured to the cam plates by welding or the like. The plates have a flange conforming to the flange in the enlarged portion of the cam plates to provide further reinforcement thereof. A retainer plate 59 is provided for the rollers 35 and 36 for forming a trackway 60 for the rollers 35 and 36. The plate has its ends turned upwardly forming flanges 61 for securing the plate to the housing by set screws or the like, as indicated at 62 (Fig. 2). The plate 59 is provided with a reinforcing rib 63 to lend rigidity to the structure and retain the rollers in the trackway 60.

The supports 27 and 28 on the forward portion 16 of the spider are provided on the underneath side adjacent of the cam rollers with threaded sockets adapted to receive the shanks of the trunnions 64 for mounting of ball bearing rollers 65 and 66 which engage against the edges 67 and 68, respectively, of the inturned flanges 51 on the track plates, as best illustrated in Fig. 6, to prevent lateral movement of the spider in the housing 41.

The supports 32 and 33 of the rear portion 19 of the spider are also provided with threaded

bore adapted to receive the threaded shanks of trunnions 69 for mounting ball bearing rollers 71 and 72, also for prevention of lateral movement of the rear portion of the spider in the housing.

The bumper 73 is secured to the down turned flange 45 of the rear end of the housing by brackets 74 secured to the flange by screws 75. The bumper is hollow and the brackets extend into the ends thereof to retain the bumper on the flange so that the rear portion 19 of the spider will engage thereagainst to provide a cushion therefor. A bumper 76 is also provided at the forward end of the spider and is secured to the end 43 of the housing in a similar manner to the rear bumper as just above described, the forward bumper being in substantial alignment with the forward ends of the track-ways in the cam plates.

The end 43 of the housing is provided with an opening 77 for receiving a reduced shank portion 78 of a threaded shank 79. The reduced shank extends outwardly from the end of the housing and is provided with a hand wheel 80 which is secured on the reduced shank by suitable means, such as a socket type set screw (not shown). A cross arm 81 having a threaded center portion 82 is provided for receiving the threaded shank portion 79 and the outer ends of the arm are provided with slots 83 for receiving headed screws or stems 84 secured to the reduced ends 85 of tension springs 86. The stems 84 are provided with heads so that when tension is placed on the springs, the stems will be retained in the slots. The other ends of the tension springs are reduced as indicated at 87 and similar stems 88 are secured therein for engaging in the radial slots 40 and the heads of the stems engage around the cylindrical recesses 39 of the rear portion of the spider. Spaced from the end of the threaded shank 79 is an opening adapted to receive a cotter key 89 for preventing accidental displacement of the threaded shank from the arm.

The raised plate member 47 of the flat top of the housing 41 near the rear end thereof is cut out forming a slot 90 which is adapted to receive a horizontal arm 91 of the back member 92. A plate 93 engages over the raised plate member 47 and is provided with spaced threaded openings adapted to receive threaded shanks of bolts 94 which extend into aligned openings in the horizontal arm 91 and the raised plate member 47 to secure the horizontal arm to the top of the housing 41. The plate 93 is also secured to the top of the housing by threaded bolts 95. The respective ends of the plate extend outwardly and upwardly from the raised plate member 47 in spaced relation to the top plate of the housing for a purpose later described. The back portion 92 has an enlarged upper end 96 provided with an opening 97 for receiving a pin 98 for hingedly connecting a back adjusting member 99. The back adjusting member comprises a hollow member substantially rectangular in shape and has an open bottom end 100 and a slot 101 at its upper end for receiving the lower end 102 of a spring arm 103 to which the back portion 8 is attached. The upper end of the housing 99 of the back adjusting member is provided with forwardly extending ears 104 which engage the pin 96 for hingedly connecting the members together.

The back 8 comprises an outer plate 105 and an inner plate 106 spaced apart as best illustrated in Fig. 2. The upper end of the spring back

member 103 is secured to the inner plate 106 by bolts 107 and a strap 108 forming a loop member is provided near the lower end of the plate 105 through which the lower end of the back member extends to limit bending of the spring back member 103 and resulting relative movement of the plate 105 and spring back member. The plates 105 and 106 are of a curvature to conform to the back of the user and the forward plate is provided with the usual cushion member 109 which is covered by suitable upholstery 110. The edges of the plate and upholstery material are provided with a cushion member 111 of rubber or like material.

The back member may be raised and lowered to fit the desire of the user by moving a shank in the housing member 99 through manipulation of the hand wheel 112 having a threaded shank 113 engaging in a threaded aperture in a boss 113 and having its inner end engaging against the lower portion of the flat spring member 103, as best illustrated in Fig. 4.

In order to adjust the angle of the back to the seat portion of the chair the lower end of the housing member 99 is provided with slots 114 and 115, the slot 114 being adapted to engage the reduced portion 116 of an adjustable pin 117, the outer end being provided with a hand wheel 118. Welded to the lower side of the horizontal arm 90 of the back member is a depending lug 119 having a threaded opening adapted to receive the threaded shank 120 of the pin 117, the inner end of the pin extending through a suitable opening 121 in the rear portion of a frame 122 for the seat 5.

The seat frame 122 is a construction of a channel shaped member comprising sides 123, front portion 124 and rear portion 125, the forward corners of the frame being rounded, as indicated at 126, to provide a smooth appearance to the chair seat. Secured to the sides of the frame and running transversely of the tilting mechanism is a U-shaped inverted channel cross members 127 to add strength to the seat frame. Also secured to the seat frame are angle members 128 and 129 having their respective ends secured to the front and rear portions of the frame by welding or other suitable means, the central portions of the angle members being under and secured to the inverted channel member 127. The horizontal flanges 130 of the angle irons are so arranged as to rest on the outer edge of the top of the tilting mechanism housing 41 and are slidably retained thereon by the extended ends of the plate 93 at the rear of said housing. A strap member 131 is secured to the forward portion of the top of the housing 41 by bolts of the like 132, the ends of which also extend up and over the flanges 130 of the angle irons as best shown in Fig. 6. The plate 93 and strap member 131, therefore, retain the seat frame 122 in sliding contact with the tilting mechanism housing 41 for a purpose described below.

In order to provide for fore and aft adjustment of the seat frame relative to the housing 41 having the back member 92 secured thereto, I provide a laterally extending ear 133 secured to the side of the housing and provided with a threaded bore 134. Formed integrally with the rear portion 125 of the frame is a depending lug 135 adapted to receive a reduced portion 136 of a pin 137 having a hand wheel 138 on its outer end. The inner end of the pin is reduced and threaded as indicated at 139 and adapted to engage in the threaded bore 134.

The seat 5 comprises a supporting lower plate 140 slightly dish shaped and having a peripheral flange 141. The respective corners of the supporting plate 140 are provided with bolts 142, secured thereto as by welding or the like, adapted to receive nuts or the like 142' and engage through strap members 143, having their respective ends engaging under the inwardly extending flange 141 of the channel shaped seat member for retaining the plate on the seat frame. A cushion member 144 is provided, such as foam rubber or the like, and upholstery 145 engages over said cushion and is retained on the supporting plate 140 by suitable detachable fastening members as indicated at 146. The cover 145 is removable and replaceable as desired.

The lower flange portion 147 of the seat frame 122 is tapped around the front portion thereof and a substantial distance along the sides, as best illustrated in Fig. 3, and adapted to engage in these tapped portions are threaded bolts 148 for securing thereto a bumper 149 consisting of rubber or other pliable material. The bumper portion is enlarged as indicated at 150 and has a recess portion 151 adapted to receive a plate 152 against which the heads 153 of the bolts 145 engage to retain the bumper on the lower edge of the seat frame.

The arms 6 are secured to the seat frame member by welding or other suitable means, and include a padding covered by upholstery material, as indicated at 154.

Operation of a chair constructed and assembled as described is as follows:

35 Depth of the seat of the chair with respect to the back may be adjusted by manipulation of the hand wheel 138 which will move the seat frame forwardly or backwardly with respect to the tilting mechanism frame or housing. The height of the back 8 is adjusted by manipulation of the hand wheel 112 on the tiltable mechanism as shown in Fig. 4. Adjustment of the tilt of the back with respect to the chair and seat is accomplished by manipulation of the hand wheel 113 on the pin 117 which extends through the slots in the frame 99 and movement of the lower end thereof with respect to the back support member 92 will control the angle of the back 8, the frame 99 being pivotally mounted to the back support member 92.

50 The back 8 is mounted on the flat spring member 103 which is secured by the bolt 107 near the top thereof and the flat spring member has movement which is loosely controlled near the lower portion of the back by the strap 108 so that 55 when the user leans back, the chair seat will move forwardly, but further backward pressure will cause an additional movement of the back somewhat in the nature of a pivoted movement giving added resiliency to the back member.

60 The tilting framework mechanism is rotatably mounted on the standard or pedestal 3 to allow the chair to revolve. When the user is sitting in normal upright position, the cam rollers 30, 31, 35 and 36 will be in the position shown in Fig. 6, whereby the seat is retained in a substantially horizontal position. Movement of the body slightly backwardly will immediately cause the rollers 30, 31, 35 and 36 to move in the trackways 52 and 60. The pressure of the rollers 30 and 31 will be against the underneath side of the flange 50 of the cam plates 48. The cam rollers 35 and 36 will bear against the underneath side of the somewhat arcuate flange 55 and continued backward movement will cause the housing 41 to 75 change position to that shown in Fig. 8 whereby

at that point the user is sitting in a substantially balanced position whereby slight movement forwardly will again cause the chair seat to assume the horizontal position, the back being resiliently mounted so it will follow the back of the user at all times.

The tension of the springs 66 are controlled by the hand wheel 80 whereby adjustment is made to accommodate persons of different weight. The heavier the person the greater tension is necessary on the springs and, of course, the converse is true where lighter persons are using the chair. The tension spring mechanism also tends to maintain the chair seat in substantially horizontal position as well as to provide the desired resistance to the backward leaning action of the user on the back of the chair. The forward portion 16 of the spider 13 will contact the bumper 76 which provides a resilient stop thereof, and when the chair is tilted backwardly, the rear portion 19 of the spider 13 will contact the bumper 74 which provides a cushion effect to the tilting mechanism.

The upholstery on the chair seat, arms and back is removable should it become worn or for other reasons should have to be replaced.

It will be obvious from the foregoing that I have provided an improved posture chair whereby the seat is mounted to assume a substantially balanced position when the chair is tilted backwardly and wherein the seat goes forwardly and the forward portion upwardly coordinately with the movement of the body of the user and have also provided a resiliently mounted and adjustably tilttable back portion to accommodate persons of different sizes and weights.

What I claim and desire to secure by Letters Patent is:

1. A chair comprising, a support, a spider mounted on said support, a tilting mechanism mounted on said spider, a seat mounted on said tilting mechanism, and a back mounted on said tilting mechanism, said tilting mechanism including cam plates having flanges forming tracks, said spider having cam rollers engaging said tracks whereby said seat will move forwardly and the front portion upwardly with respect to the support as the occupant leans backwardly.

2. A chair comprising, a support, a spider mounted on said support, a tilting mechanism mounted on said spider, a seat mounted on said tilting mechanism, and a back mounted on said tilting mechanism, said tilting mechanism including spaced cam plates having flanges forming tracks, one end of said plates being enlarged and slightly arcuate-shaped and forming tracks at an angle to the other tracks, said spider having cam rollers engaging said tracks whereby said seat will move forwardly and the front portion upwardly with respect to the support as the occupant leans backwardly.

3. A chair comprising, a supporting pedestal, a spider rotatably mounted on said pedestal, a tilting mechanism mounted on said spider including a frame, a seat mounted on said frame, a back mounted on said tilting mechanism, said tilting mechanism including cam plates secured to the inner walls of said frame and having flanges forming tracks, said spider having cam rollers engaging said tracks whereby said seat will move forwardly and the front portion thereof upwardly with respect to the support as the occupant leans backwardly, and means on the spider having engagement with the frame for preventing lateral movement of the frame relative to the spider.

4. A chair comprising, a supporting pedestal, a spider rotatably mounted on said pedestal, a housing for said spider having cam plates secured to the respective inner walls thereof, said cam plates having enlarged rear ends and having substantially horizontal tracks near their forward ends and slightly arcuate tracks at their rear ends, cam rollers carried by the respective ends of said spider engaging said tracks, a seat on said housing, spring tension means interconnected with the housing and spider for normally maintaining the seat in horizontal position, and a back mounted on said housing.

5. A chair comprising, a support, a spider mounted on said support, a tilting mechanism mounted on said spider including a frame slidably mounted thereon, a seat on said frame, a back mounted on said tilting mechanism, said tilting mechanism including cam plates having flanges forming tracks, one end of each of said plates being enlarged and one of the tracks being slightly arcuate and at an angle to the other track, said spider having cam rollers engaging said tracks whereby said seat will move forwardly and the front portion upwardly with respect to the support as the occupant leans backwardly, and means interconnecting said frame and said tilting mechanism for moving the frame and seat forwardly and backwardly with respect to said back.

6. A chair comprising, a support, a spider mounted on said support, a tilting mechanism mounted on said spider, a seat mounted on said tilting mechanism and having a rubber bumper around the lower forward edge thereof, a back mounted on said tilting mechanism, said tilting mechanism including cam plates having flanges forming tracks, one end of each of said plates being enlarged and one of the tracks being slightly arcuate and at an angle to the other track, said spider having cam rollers engaging said tracks whereby said seat will move forwardly and the front portion upwardly with respect to the support as the occupant leans backwardly, and bumper means for said spider at the extreme ends of said tracks.

7. A chair comprising, a support, a spider mounted on said support, a tilting mechanism mounted on said spider, a seat mounted on said tilting mechanism, a back mounted on said tilting mechanism, said tilting mechanism including cam plates having flanges forming tracks, one end of each of said plates being enlarged and one of the tracks being slightly arcuate and at an angle to the other track, said spider having cam rollers engaging said tracks whereby said seat will move forwardly and the front portion thereof upwardly with respect to the support as the occupant leans backwardly, bumper means for said spider at the extreme ends of said tracks, and means on said spider having engagement with said tracks for preventing lateral movement of the tilting mechanism with respect to said spider.

8. A chair comprising, a supporting pedestal, a spider rotatably mounted on said pedestal having laterally extending arms at its respective ends, a housing for said spider having cam plates with laterally turned flanges secured to the respective inner walls thereof, said cam plates having enlarged rear ends and said flanges forming horizontal tracks toward their forward ends and tracks at their rear ends extending at an angle to the horizontal tracks, cam rollers carried by the respective ends of the arms of said spider en-

gaging said tracks, rollers on the arms of said spider engaging the flanges of said tracks for retaining the housing in longitudinal alignment with the spider, a seat on said housing, spring tension means interconnected with the housing and spider for normally maintaining the seat in horizontal position, and a back mounted on said housing.

ROY A. CRAMER.
